(57) **CLAIM**

The ornamental design for a basketball hoop, as shown and described.

DESCRIPTION

FIG. 1 is a top, front, left side perspective view of a basketball hoop showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another top, front perspective view of the basketball hoop with backboard in folding state.

The broken lines in the drawings illustrate portions of the basketball hoop that form no part of the claimed design.
